CLAIM

The ornamental design for a metal brake shim with surface having an appearance of carbon fiber, as shown and described.

DESCRIPTION

FIG. 1 is a perspective view of a metal brake shim with surface having an appearance of carbon fiber according to a first embodiment of the present design.

FIG. 2 is a top plan view of the metal brake shim with surface having an appearance of carbon fiber design of FIG. 1 (with a bottom view being a mirror image thereof).

FIG. 3 is a perspective view of a metal brake shim with surface having an appearance of carbon fiber according to a second embodiment of the present design

FIG. 4 is a top plan view of the metal brake shim with surface having an appearance of carbon fiber design of FIG. 3 (with a bottom view being a mirror image thereof).

FIG. 5 is a perspective view of a metal brake shim with surface having an appearance of carbon fiber according to a third embodiment of the present design; and,

FIG. 6 is a top plan view of the metal brake shim with surface having an appearance of carbon fiber design of FIG. 5 (with a bottom view being a mirror image thereof). The broken line in the drawings depicts unclaimed portion of the brake shim only and forms no part of the claimed design.
